(57) **CLAIM**

We claim the ornamental design for a cabinet assembly, as shown and described.

DESCRIPTION

FIG. 1 is a top, right perspective view of a cabinet assembly showing our new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

Broken lines in the drawings show portions of the cabinet assembly that form no part of the claimed design.

1 Claim, 6 Drawing Sheets
